G. I. HANCOCK,
STAMP CANCELING DEVICE,
APPLICATION FILED JUNE 23, 1915.

1,164,811.

Patented Dec. 21, 1915.

UNITED STATES PATENT OFFICE.

GEORGE I. HANCOCK, OF VANOV, GEORGIA.

STAMP-CANCELING DEVICE.

1,164,811.

Specification of Letters Patent. Patented Dec. 21, 1915.

Application filed June 23, 1915. Serial No. 35,965.

To all whom it may concern:

Be it known that I, GEORGE I. HANCOCK, a citizen of the United States, residing at Vanoy, in the county of Crawford and State of Georgia, have invented new and useful Improvements in Stamp-Canceling Devices, of which the following is a specification.

This invention relates to improvements in stamp canceling devices, of the character employed by post-masters and other postal officials for the purpose of simultaneously canceling the stamp upon a piece of mail matter and indicating thereon the name of the post-office and other desired data or information.

The object of the invention is to provide a simple and effective device of the character and for the purpose described, whereby the operation of stamping a quantity of mail matter may be quickly and efficiently performed.

A further object of the invention is to provide a stamp canceling and post-marking device which is adjustable for stamping mail matter of different thicknesses.

The invention consists of the features of construction, combination and arrangement of parts herein fully described and claimed, reference being had to the accompanying drawing in which:—

Figure 1 is a side elevation of a stamp canceling and post-marking device embodying my invention. Fig. 2 is a top plan view of the same. Fig. 3 is a perspective view of the stamping and post-marking die. Fig. 4 is a section on line 4—4 of Fig. 2.

Referring to the drawings, 1 designates a base plate, of rectangular or oblong rectangular form and of proper thickness to support the piece of mail matter and sustain the impact of the stamping device, which plate may be disposed for use upon a bench, table or desk, and secured thereto if desired in any suitable manner.

Rising from the base plate are walls or flanges 2 and 3 which intersect at one end and form a space 4 upon the plate to receive the letters and other mail matter to be stamped, one of the longitudinal and one of the transverse edges of each letter or other article are designed to be brought to bear against the surfaces 2 and 3 to properly position the stamp at the corner of the envelope in the corner formed at the point of intersection of said walls, for the cancellation of the stamp and the imprinting upon the en-

velop or piece of mail matter of the post-mark.

Rising from the base plate is a guideway formed by uprights 5, provided on their inner faces with guide grooves 6 to receive guide tongues 7 on a carrier block or bracket 8. This carrier block or bracket is provided with an upstanding lug 9 fitting between the arms 10 of the bifurcated end of a carrier plate 11, the said arms 10 being pivotally connected with the lug 9 by a pivot pin or bolt 11'.

The free end of the carrier plate 11 is provided with a finger piece or handle 12, and said plate carries a die proper 13 bearing upon its lower surface printing elements 14 for canceling a stamp and a post-marking stamp 15, which may be of a character to admit of date changes or other changes so that the name of the post-office, date of deposit of the mail matter and other appropriate information may be printed.

It will be understood from the foregoing description that when the device is used the carrier plate, forming a part of the die or stamping device as a whole, is raised, the mail matter to be stamped inserted thereunder so that the stamp carrying corner will be disposed in the angle between the connecting ends of the flanges 3, and the die or stamping device then brought down with proper force for the stamp canceling and post-marking action. It will of course be understood that the die may be either hand or self-inked, no inking means being shown, as this forms no part of the present invention.

Owing to the fact that the die may be quickly raised and forced downward, and to the fact that the mail matter may be quickly and accurately inserted in place, it will be apparent that by means of the device a large amount of mail matter may be stamped within a minimum period of time.

For the purpose of adjusting the carrier block and die to different elevations, to accord with different thicknesses of envelopes, packages or other mail matter to be stamped and post-marked, I provide the block or bracket 8 with gear teeth 16 meshing with an adjusting gear or pinion 17. This gear or pinion is mounted on a shaft 18 journaled in bearings 19 on the base plate 1 and on which is also mounted a locking pinion 17', said shaft being provided at one end with a handle 20 by means of which the gear may

be turned to adjust the carrier block up or down. The bearings 19 are suitably fastened to the base plate, and one of said bearings is mounted upon a frame piece having 5 an arm 21 arranged in spaced relation to an upright 22 rising from the base plate, in which arms are slidably mounted a dog or pawl 23 adapted for engagement with the pinion 17' to lock said pinion and the block 10 8 in adjusted position, the dog being maintained normally in locking position by a coiled spring 25 and being provided with a handle or finger piece 26 whereby it may be retracted.

15 I claim:—

1. A device of the character described comprising a base plate, a guideway upon the base plate, a pivotally mounted stamping member, a support for said stamping member, means mounting said support upon the base plate for adjustment to different elevations, and means for holding said support in different positions of adjustment.

2. A device of the character described

comprising a base plate, a guideway upon 25 the base plate, a carrier block adjustably mounted in said guideway, a die upon the carrier block, means adjustably mounting said carrier block and engaging said guideway, adjusting means for adjustable mounting, and means for locking said adjusting means in different positions.

3. A device of the character described comprising a base plate, a guideway rising therefrom, a supporting block adjustable in 35 said guideway, a guide pivotally mounted upon said carrier block, a gear in mesh with the carrier block whereby said carrier block may be vertically adjusted, a locking device for holding the gear in adjusted position, 40 and a spring for holding the locking device normally in locking position.

In testimony whereof I affix my signature in presence of two witnesses.

GEORGE I. HANCOCK.

Witnesses:
